UNITED STATES PATENT OFFICE.

THOMAS J. BUTLER, OF HARRISON, NEW JERSEY.

MOTOR BOAT AND PROPELLING MEANS THEREFOR.

Application filed August 19, 1925. Serial No. 51,148.

This invention relates, generally, to improvements in motor-propelled boats; and, the present invention has reference, more particularly, to the provision of a boat with a gasoline-driven engine, preferably of the "Ford" type, combining with the general arrangement of the motor within the boat, a novel cooling system for cooling the engine; and, furthermore, by means of the cooling system also cooling the oil used in the casing of the engine.

The invention, therefore, has for its principal objects to provide a motor-boat operated, preferably, from a "Ford" motor; and, furthermore, to provide a novel and simply constructed cooling system for cooling the engine, as well as the oil used, by taking from a point outside of the boat a continuous supply of normally cold water, and discharging the water at another point outside of the boat, after the cooling operation has been performed.

Other objects of the present invention not at this time more particularly enumerated will be more fully understood from the following detailed description of the present invention.

With the various objects of the present invention in view, the invention consists, primarily in the novel motor-driven boat hereinafter more fully set forth; and, the invention consists, furthermore, in the general arrangements and combinations of the various devices and parts, as well as in the details of the construction of the said parts, all of which will be more fully described in the following specification, and then finally embodied in the clauses of the claims, which are appended to and which form an essential part of the said specification.

The invention is illustrated in the accompanying drawings, in which:—

Figure 1 is a side view of a boat driven in the manner of the present invention, showing in connection with the hull or body of the boat, the intake end and the discharge end of the piping used with the water cooling system.

Figures 2 and 3 are longitudinal vertical sections of the bow-end of the boat, illustrating in connection therewith and in elevation, the reverse sides of a motor and a cooling system embodying the principles of the invention.

Figure 4 is a longitudinal vertical section

of one of the cooling members of the system, said section being taken on line 4—4 in Figure 3; Figure 5 is a view, partly in elevation and partly in longitudinal vertical section, of a water-cooled muffler; and Figure 6 is a transverse vertical section of the same, said section being taken on line 6—6 in said Figure 5.

Figure 7 is a detail view, showing diagrammatically, the inlet-portion of a carburetor, a portion of the feed-pipe leading to said inlet-portion, and a portion of the overflow pipe or trap connected with said feed-pipe; and Figure 8 is a detail sectional representation of a certain portion of the device, being represented as taken on line 8—8 in Figure 3.

Similar characters of reference are employed in all of the said above described views, to indicate corresponding parts.

Referring now to the several figures of the drawings, the reference-character 1 indicates the hull or body of a suitably-shaped boat formed with a suitable compartment, as 2.

Suitably disposed in the forward portion of this compartment is a gasoline motor or engine preferably of the "Ford" type, of which 3 represents the usual engine-casing. The reference-character 4 indicates the main shaft of the motor or engine, said shaft having suitably mounted thereon a pulley-wheel 5 over which is passed a driving belt 7. Suitably mounted upon a portion 8 of the casing 3 is a bracket 9 to which is suitably secured a pump 10 of any desired construction, the pump-shaft of which is indicated by the reference-character 11. Mounted upon this shaft 11 is a pulley-wheel 12, which is adapted to be operated from the driving belt 7, as will be evident. Connected with the inlet 13 of said pump 10 is a supply pipe 14, which extends through the hull or body of the boat for taking in water from outside of the boat and delivering it into the pump, when the latter is set in motion. Connected with the exit or delivery-portion 15 of the pump 10 is a pipe 16 which leads to and is connected with a suitable water-jacket or casing 17.

Referring to Figure 4 of the drawings, it will be seen that this water-jacket or casing is provided with leak-proof or water-tight ends 18 and 19, and has an outlet 20, suitably located in its side. Connected with this outlet 20 is a conveyor-pipe 110

21 which leads to and is connected with an the gear-mechanism, so as to propel the boat inlet 22 with which the water-jacketed casing 3 is provided.

From the above description it will be evident, that I have provided a simple as well as an efficiently operating cooling system for continuously cooling the motor or engine with the normally cold water, taken in at the bow and discharged at the stern 10 of the boat, the arrangement and construction of the cooling system also being such, that the circulating water may be used for cooling the muffler and the exhaust gases discharged into the same, thereby minimizing any back-fire, and consequent danger 15 of fire.

Referring now to Figure 3 of the drawings, it will be seen that the lubricating oil, which circulates from the transmission-portion 47 of the casing 3, through said casing and back to the transmission may be suitably cooled.

This is accomplished by connection with the portion 47, as at 48, of a pipe 49, which 25 pipe leads into and from the water-jacket or casing 17, as indicated in Figure 4 of the drawings, and which pipe 49 is connected with a suitably placed and suitably constructed oil-screening appliance, as 50, said 30 device being provided with an outlet 51 which is connected with the casing 3, as at 52, and communicates with the interior of said engine-casing.

In order that the oil from the transmission 35 may readily pass into the pipe 49, a suitably shaped scoop or deflector 53, see Figure 8, may be suitably located within the transmission casing-portion 47, onto which the oil is splashed so as to readily flow into 40 the pipe 48, as will be evident.

Forward and rearward propulsion of the boat is produced by the mechanism illustrated in Figure 3 of the drawings, in which the reference-characters 65 and 66 indicate the actuating shafts of the gear-shift mechanism, enclosed in the engine-casing 3 in the usual manner. As indicated in said Figure 3, the said casing is made with an extension 67, provided with a bearing in 50 which is mounted a pintle 68. Suitably secured upon said pintle in fixed angular relation to each other is a lever 69 and a pair of upwardly extending actuating members, as 70 and 71. Suitably connected with the shaft 65 is a crank 72, with the free end-portion of which is pivotally connected a link-member 73 which is also pivotally connected with the member 74 of the lever 69. Similarly mounted upon the shaft 66 55 is a crank 75, the free end-portion of which is operatively connected in any suitable manner, with the portion 76 of the above-mentioned member 71. The manner of actuating the shafts 65 and 66, by means of 60 the lever 69, for correspondingly shifting

in a forward or rearward direction will be fully understood from an inspection of said Figure 3 of the drawings. The reference-character 77 indicates the usual speed-control means or auxilerator, which is suitably actuated from the cam-portion 78 of the member 71, as the lever 69 is moved back and forth.

From the foregoing description of the present invention, it will be evident, that I have produced a simple arrangement of devices which enables the adaptation of the Ford engine to a motor-boat.

I am aware, also, that changes may be made in the general arrangements and combinations of the various devices and parts, as well as in the details of the construction of the said parts, without departing from the scope of the present invention as set forth in the foregoing specification, and as defined in the clauses of the claims which are appended thereto. Hence, I do not limit my present invention to the exact arrangements and combinations of the various devices and parts as described in the said specification, nor do I confine myself to the exact details of the construction of the said parts, as illustrated in the accompanying drawings.

I claim:—

1. In a motor-boat, in combination with the hull of the boat, provided with a means of ingress and a means of egress, an engine and its casing, a pump, means for driving said pump from the engine, oil-conveying means associated with the engine-casing for conveying oil at one point from within said casing to the outside thereof and at another point back into said casing, water-conveying means between said means of ingress, said pump, said oil-conveying means and the engine, for cooling the oil as it passes through said oil-conveying means, and also for cooling the engine, and a water-conveying means between the engine and the said means of egress.

2. In a motor-boat, in combination with the hull of the boat, provided with a means of ingress and a means of egress, an engine and its casing, an oil-conveying pipe associated with said casing for conveying oil at one point from within said casing to the outside thereof and at another point back into said casing, a water-jacket surrounding said pipe, a water-conveying means between said means of ingress and said water-jacket, and a water-conveying means between said water-jacket and the engine-casing, for cooling the oil as it passes through said oil-conveying pipe, and also for cooling the engine, and a water-conveying means between the engine and said means of egress.

3. In a motor-boat, in combination with the hull of the boat, provided with a means

of ingress and a means of egress, an engine and its casing, a pump, means for driving said pump from the engine, an oil-conveying pipe associated with said casing for conveying oil at one point from within said casing to the outside thereof and at another point back into said casing, a water-jacket surrounding said pipe, a water-conveying means between said means of ingress and the pump, a water-conveying means between the pump and the water-jacket of said oil-

conveying pipe, and a water-conveying means between said water-jacket and the engine-casing, for cooling the oil as it passes through said oil-conveying pipe, and also 15 for cooling the engine, and a water-conveying means between the engine and said means of egress.

In testimony that I claim the invention set forth above I have hereunto set my hand 20 this 31st day of July, 1925.

THOMAS J. BUTLER.
